PLANTER MARKER CONTROL

Arthur J. Immesoete, Moline, Ill., assignor, by mesne assignments, to Deere & Company, a corporation of Delaware

Filed Mar. 27, 1957, Ser. No. 648,864

10 Claims. (Cl. 172—128)

The present invention relates generally to agricultural implements and more particularly to marker means for such implements as planters and the like.

The object and general nature of the present invention is the provision of an implement, such as a planter, having new and improved marker means and new and improved means for controlling the marker arms. More specifically, it is a feature of this invention to provide generally laterally inwardly and outwardly swinging marker arms, with means for swinging the marker arms from one position to another that derives operating energy from the means for raising and lowering the implement into and out of its transport or non-working position. More particularly, it is a feature of the present invention to provide means for actuating the marker arms that is connected with the generally vertically swingable wheel frame that is raised and lowered relative to the main frame of the implement.

Another important feature of the present invention is the provision of new and improved marker controlling latch means operating in conjunction with a flexible element extending across the front of the implement and connected at its end with the marker arms, with means for maintaining said element taut both in the transport and in the operating positions of the marker arms.

A further feature of this invention is the provision of means for supporting the marker arms positively and securely when transporting the implement over relatively long distances so that under practically all circumstances the inadvertent lowering of the marker arms or movement of them out of their transport position is prevented. Still further, in this connection another feature of this invention is the provision of means whereby inadvertent swinging of the marker arms into their transport brackets is prevented when such action is not desired.

Another feature of this invention is the provision of a new and improved marker arm arrangement in which the marking element includes a disk, which can accommodate a greater amount of trash and the like than other types of marking elements, with means mounting the marker disks so that they are always disposed at an angle to the line of travel and will therefore encounter sufficient soil resistance so that the marker arms will swing backwardly into operating position quickly and without delay.

These and other objects and advantages of the present invention will be apparent to those skilled in the art after a consideration of the following detailed description, taken in conjunction with the accompanying drawings, in which:

Fig. 1 is a perspective view of a four-row planter in which the principles of this invention have been incorporated.

Fig. 2 is a fragmentary view of the means holding the marker latch chain taut when both marker arms are swung forwardly into their raised or transport position.

Fig. 3 is an enlarged fragmentary view showing the marker arm operating means by which the down marker arm is swung toward its transport position by the lowering movement of the associated wheel frame of the implement.

2

Fig. 4 is an enlarged fragmentary view showing the mounting of the latch controlling rod, and associated parts.

Fig. 5 is a fragmentary view, diagrammatic in character, illustrating the angular relation between the marker disk and the direction of travel when the marker arm swings from transport or inoperative position laterally outwardly to a working position.

Referring first to Fig. 1, the implement in which the principles of this invention have been incorporated is shown as a planter, indicated in its entirety by the reference numeral 10. The planter includes a main frame 11 that is made up of a rear bar section 12, end sections 13, and generally forward and laterally and inwardly directed frame sections 14. Generally, the sections 12, 13 and 14 comprise a channel member bent to the configuration shown, with the inner adjacent portions of the end sections 14 secured, as by welding or the like, to a short sleeve 16 that receives the rear end of a draft or hitch member that preferably is in the form of a pipe 15. The frame 11 is completed by a plurality of fore-and-aft extending bars 17, 18 and 19, and other laterally extending bars 21 and 22, at each side of the frame, all bolted or welded together to form a rigid framework. Mounted on each set of transverse bars 21 and 22 is a furrow opener unit 25 and an associated seed hopper 26, the latter also containing suitable seed dispensing mechanism. Through suitable front and rear brackets 28 and 29 the frame 11 also carries fertilizer tanks 31. The rear end of the draft pipe 15 is removably disposed in the sleeve 16 and the latter is secured, as by welding, to a cross bar 32, as shown in Fig. 1.

The frame 11 and associated parts are supported on a wheel carrier unit 35. This unit includes a wheel frame 36 that is made up of a generally transversely disposed pipe member 37, forming a rockshaft, that is journaled for rocking movement in a plurality of bearing brackets, one of which is indicated at 38 in Fig. 3. These brackets are carried by the rear bar section 12 of the frame 11. A pair of inner and outer arms 41 and 42 are fixed to each end of the rockshaft 37 and at their outer ends rotatably receive a ground wheel 43. An arm 45 is fixed to the generally central portion of the rockshaft 37 and is connected by a link 46 with an arm 47 that is journaled in a bracket 48 carried at the rear end of the sleeve member 16. The latter member also carries a forward bracket 50, and a power cylinder (not shown) is adapted to be connected between the bracket 50 and the upper end of the arm 47, whereby the power cylinder serves as means for rocking the wheel frame for raising and lowering the main frame 11 and associated parts. Movement of the wheel frame 36 relative to the main frame 11 is made use of, according to the present invention, for raising and lowering the marker arms, and the mechanism for this purpose will now be described.

Referring first to the marker arm construction, a marker arm support 51 is fixed to each rear corner of the main frame 11, each support including a generally vertically disposed rod 52 and a pair of apertured bracket plates 53 welded to the lower portion thereof and apertured to receive bolts 54 or other means fastening the support 51 to the main frame. The rod 52 extends downwardly at its lower end and loosely receives the associated marker arm 55, the latter being swingable generally in a horizontal plane and also upwardly and downwardly relative thereto through a limited extent. The upper portion 57 of the supporting rod 52 is extended upwardly and rearwardly and an elevating chain section 58 is connected at its upper end to the upper portion of the rod section 57, the chain section 58 extending forwardly and being connected, as at 59, shown in the right hand portion of Fig. 1. Since the upper end of the rod support 52 is

disposed a considerable distance outwardly and rearwardly of the lower pivotal connection between the marker arm 55 and its support rod 52, when the marker arm extends generally laterally outwardly away from the frame 11, the outer end of the marker arm is disposed in a lower portion, but when the arm 55 is swung around forwardly and laterally inwardly toward the side of the frame 11, the marker arm 55 is raised, as shown in the right hand portion of Fig. 1. The marker arm 55 shown in the left hand portion of Fig. 1 is in its lowered or operating position. Any suitable marking element may be fixed to the outer end of each marker arm 55, but I prefer to use, especially when operating under trashy conditions, a mark-forming disk 61. The mark-forming disk 61 is mounted on the outer end of the associated marker arm 55 in a special way so that automatic movement of the marker arm laterally outwardly and rearwardly to its operating or mark-forming position will be assured. Reference to this action will be made later.

As was mentioned above, to raise the marker arms into an inoperative transport position, it is a feature of this invention to utilize a movement of the wheel frame 36 relative to the main frame. For this purpose, a lifting chain 65 is provided for each marker arm 55. The innermost end of each chain 65 is connected to the outer wheel arm 41 in any suitable way and the chain extends therefrom upwardly through a first sheave 66 and then rearwardly and around a second sheave 67, both being carried by the associated frame bar 19. From the sheave 67, the chain 65 extends laterally outwardly through a supporting clip 68 and an aperture 69 formed in the side section 13. The laterally outer end of the chain 65 is connected by a cotter 71 or any suitable means to the adjacent portion of the arm 55. As will best be seen from Fig. 3, in which the wheel frame is shown in its upper position, which disposes the furrow openers 25 in a ground working position, the chain 65 has sufficient slack therein to accommodate movement of the marker arm 55 laterally outwardly and rearwardly to about the position shown in full lines in Fig. 3, which corresponds to the position shown in the left hand portion of Fig. 1. As will be understood from Fig. 3, whenever the wheel frame 36 is swung downwardly to raise the main frame and associated furrow openers and other parts into a transport position, out of contact with the ground, the resulting downward movement of the forward ends of the arm will exert a pull through the associated chains 65 and raise either or both of the marker arms 55 into a transport position. During this action the marker arm being raised is swung forwardly by virtue of the pull exerted thereon by the chain 65, and as the marker arm 55 is swung forwardly the chain section 58 also causes the same to be elevated. As a result of this action, the marker arm 55 is swung into a position closely adjacent that indicated in dotted lines in Fig. 3. It will be understood, first, that normally only one marker arm is in operating position at any one time, the other marker arm being held in a transport or inoperative position, and therefore whenever the wheel frame is lowered to raise the main frame, only the lowered marker arm will be raised.

Fig. 3 also shows a feature of the present invention wherein a transport bracket, indicated in its entirety by the reference numeral 75, is provided at each end of the frame 11. Each bracket 75 comprises an upwardly extending U-shaped bracket section, formed by legs 76 and 77 the lower portions of which are fixed, as by welding or the like, through a horizontal bracket section 78 that is fixed, as by a bolt 79, to the associated side section of the main frame 11. The bolt 79 may be one of two bolts, shown at 79 and 81, that connect the associated crossbar 22 in place. For ordinary operation, as when turning at the end of the field or the like, the marker arm 55 is not carried in the transport bracket 75. However, whenever the implement is to be transported considerable distances, both marker arms 55 are adapted to be lifted manually

into the bracket 75, the legs 76 and 77 of which are apertured to receive a retaining pin 82. By disposing the marker arm 55 in the transport brackets 75, the chains are relieved of holding the marker arms in their elevated position and by the use of the retaining pins 82, there is no likelihood that the marker arms 55 may become accidentally disconnected which, if permitted to occur, might cause one or both of the marker arms 55 to collide with adjacent objects, such as a fence, buildings or the like when transporting the implement.

As can be seen from Figs. 1 and 3, the retaining pins 82 are considerably longer than the distance between the associated bracket legs 76 and 77. When the pins 82 are used to retain the marker arms 55 in the associated bracket 75, the long ends of the pins are disposed laterally inwardly, but when in operation after the marker arms 55 have been manually released from the brackets 75, the long ends of the pins 82 are disposed laterally outwardly, as shown in Fig. 1. This provides a means which acts to prevent either the marker arms from being swung upwardly with sufficient velocity to cause them to collide with and possibly rebound into the associated bracket 75. If this were permitted to occur, during operation, the marker arm could not be automatically lowered by movement of the wheel frame until the operator manually released the marker arm from the bracket 75.

New and improved latch means for controlling the marker arms will now be described.

A transverse chain 91 is extended from one marker arm across the front of the machine to the other marker arm, and preferably, but not necessarily, the chain sections 58 described above form the outer ends of the transverse chain 91. The chain passes along in front of the end frame sections 14, being extended through guide clips 92 which form abutments cooperating with stops 93 carried by the chain. Each stop 93 is adjustable along the chain so that when the stop 93 engages the abutment 92, the associated marker arm 55 is held in the desired laterally outwardly extending or operating position. The generally central portion of the chain 91 is formed with loop portions 95, these portions of the chain 91 passing around sheaves 96 that are carried for rotation on a suitable upwardly and forwardly extending bracket 98 fixed to the forward central portion of the main frame 11, preferably the portion through which the hitch pipe 15 extends, as best shown in Fig. 1. The bracket 98 carries suitable means 101 on which the sheaves 96 are journaled, and this means also forms a support for an upper angle bracket 102, the upper flange 103 of which is apertured to receive a latch controlling rod 104. The rod 104 extends forwardly and upwardly, as best shown in Fig. 1, and at its upper end is supported on a strut 105 fastened at its lower end to the forward portion of the hitch pipe 15. The bracket 102 also supports a snap action type of latch member 106 (Fig. 4) that is adapted to clamp against one or the other of the associated chain sections that pass around the sheaves 96. When, for example, the part 106 is held against the chain section that passes around one of the sheaves 96, that chain section is, in effect, locked, and thus holds the associated marker arm against downward and outward movement, even though the wheel frame should be raised relative to the main frame. However, the other chain section is released, so that when the wheel frame is raised, the marker arm associated with said other chain section is permitted to lower. As shown in Fig. 4, the upper chain section is latched against the associated sheave while the lower chain section and its associated sheave 96 is free to move. The latch member 106 is controlled by an arm 109 that lies just underneath the lowermost end portion 111 of the control rod 104. The latter carries a yoke 112 having ends 113 and 114 that are adapted to swing the control part 109 from one side to the other. The present invention is not particularly concerned with the

details of the latching means, and therefore the same has been illustrated only fragmentarily in Fig. 4.

The loop section 95 of the chain 91 is adapted to extend upwardly and forwardly along the underside of the rod 104 when both abutment arms are raised. This loop section 95 at its uppermost portion is trained over a smoothly curved section 115 found on a slide 116 that is movable along the rod 104. A spring 117 is connected at its lower end to the slide 116 and at its upper end to a portion 118 of the rod support 105. The spring 117 exerts sufficient tension against the loop portion 95 of the chain to take up all slack or looseness therein, which might otherwise occur when both marker arms are in their raised position, the chain 91 having sufficient length to accommodate one arm being in its lowered or rearward operating position while the other arm is raised, as shown in Fig. 1. Therefore, when both marker arms are swung forwardly into their raised or transport position, without the spring 117 and associated parts, the chain 91 might be sufficiently slack to permit the lower portion thereof to come into contact with objects on the ground, which would, of course, be undesirable. In this respect, the rod 104 serves two purposes, one being to actuate the marker arm controlling latch means and the other to provide a sliding support for the spring biased part 116 that is yieldingly urged upwardly, thus eliminating all slack in the chain 91 when both marker arms are raised.

Referring now to Fig. 5 it will be seen that each marking disk 61 is fixed to the associated arm 55 by bracket means 125 that is so constructed and arranged that the plane of the disk 61, indicated at P, lies in a vertical forwardly converging relationship when the arm 55 is extended laterally outwardly in operating position. By virtue of this arrangement, when the marker arm 55 swings outwardly and rearwardly from its transport position, the disk 61 will engage the ground in such a way that at no time will the plane P of the disk lie parallel to the direction of forward travel. If this were permitted to occur, the disk might continue to rotate in that plane and, at least under certain conditions, not cause the marker arm to continue its outward movement. Arranging the marker disks 61 in the manner shown, insures that there always is sufficient soil resistance acting against the disk to swing the marker arm to its laterally outwardly extending or operating position.

While I have shown and described above the preferred structure in which the principles of the present invention have been incorporated, it is to be understood that my invention is not to be limited to the particular details, shown and described above, but that, in fact, widely different means may be employed in the practice of the broader aspects of my invention.

What I claim, therefore, and desire to secure by Letters Patent is:

1. An agricultural implement comprising a main frame having side sections and a rear section disposed generally transversely relative to the normal direction of travel, a wheel frame swingably connected with the rear section of said main frame for generally vertical movement relative thereto, a pair of marker arms swingably connected with the rear portions of said side sections, respectively, and adapted to swing generally laterally inwardly and outwardly relative to the main frame, said side sections being apertured, and a flexible connection between each marker arm and the adjacent portion of said wheel frame, each connection extending through the aperture in the adjacent main frame side section to the wheel frame, said connections serving to swing the marker arms laterally inwardly and upwardly relative to the main frame whenever said wheel frame is lowered relative to the main frame.

2. An agricultural implement comprising a main frame, a wheel frame swingably connected with said main frame for generally vertical movement relative thereto, a pair

of marker arms swingably connected with said main frame and movable between operative and inoperative positions, a connection between said wheel frame and said marker arms for raising the latter when said wheel frame is lowered relative to the main frame, a latching connection extending from one marker generally transversely of the main frame to the other marker arm and movable transversely of said main frame when either marker arm is raised or lowered, said latching connection being separate from the connection between the wheel frame and the marker arms, and latch means carried by said main frame and engageable with said latching connection for holding one or the other of said marker arms in a raised position when the wheel frame is raised relative to the main frame.

3. An agricultural implement comprising a main frame, a pair of marker arms swingably connected with said main frame and movable generally laterally inwardly and outwardly relative to the main frame between operative and inoperative positions, flexible means interconnecting the outer portions of said arms for causing one arm to be swung inwardly toward said main frame when the other is swung outwardly away from said main frame, manually controlled means acting against said flexible means for selectively locking one or the other of said arms against outward movement relative to said main frame, and means separate from said flexible means for swinging said both of marker arms laterally inwardly relative to said main frame.

30 4. The invention set forth in claim 3, further characterized by said flexible interconnecting means comprising a flexible element having a central loop portion, trained over a pair of sheaves over which said flexible element adjacent said loop is trained, and spring means 35 acting against said loop to take up slack in said flexible element when both of said marker arms are swung into their laterally inner position.

5. In an agricultural implement, having a frame and a pair of generally inwardly and outwardly swingable marker arms, the improvement comprising marker arm control means that includes a transversely movable flexible element connected at its ends with said marker arms, a generally upwardly extending part carried by said frame, a pair of sheaves carried by the lower portion of said part, said flexible element having a loop portion extended between and passing over said sheaves and extending generally upwardly along said part, means movable along said part to support said loop portion, and latch means movably carried by said frame and adapted to clamp portions of said flexible element against said sheaves, optionally.

40 6. In an agricultural implement, having a frame and a pair of generally inwardly and outwardly swingable marker arms, the improvement comprising marker arm control means that includes a transversely movable flexible element connected at its ends with said marker arms, a pair of sheaves carried by said frame, said flexible element having a loop portion extended between and passing over said sheaves, means serving as an outwardly extending support, a slide movably carried by said support means and receiving the outer part of said loop, and spring means connected to act between said support and said slide to keep said flexible element taut in different positions of said marker arms.

55 7. In an agricultural implement, having a frame and a pair of generally inwardly and outwardly swingable marker arms, the improvement comprising marker arm control means that includes a transversely movable flexible element connected at its ends with said marker arms, a pair of sheaves carried by said frame, said flexible element having a loop portion extended between and passing over said sheaves, a latching member movable between said sheaves for optionally locking the associated portions of said flexible element, against said sheaves, so as to hold one or the other of said marker arms in ele-

vated position, means including an upwardly and forwardly extending rockable member connected to operate said latching member for releasing one or the other of said marker arms, a part slidably mounted on said rockable member and carrying sheave means receiving and supporting said loop portion, and a spring connected between said loop portion and said rockable member for yieldably holding said slidably part in an upper position.

8. In an agricultural implement including a frame, marker means comprising a pair of marker arms swingably connected at their rear ends to opposite sides of said frame and movable generally horizontally between an inoperative position alongside the sides of the frame and extending generally forwardly and an operative position extending generally laterally outwardly of the sides of the frame, a marker disk at the outer end of each marker arm, and means mounting each disk on the associated marker arm at an angle to the marker arm, the angle of the disk being such that the generally vertical plane of the disk extends outwardly and forwardly of the frame when the associated marker arm extends forwardly generally alongside the frame and outwardly and rearwardly when the marker arm extends generally laterally outwardly whereby, as the marker arm moves from its inoperative position to its operative position, said disk is always angled relative to the direction of travel of the implement.

9. An agricultural implement comprising a main frame having side sections and a rear section disposed generally transversely relative to the normal direction of travel, a wheel frame swingably connected with the rear section of said main frame for generally vertical movement relative thereto, a pair of marker arms swingably connected with the rear portions of said side sections, respectively, and adapted to swing generally laterally inwardly and outwardly relative to the main frame, and a flexible connection between each marker arm and the adjacent por-

tion of said wheel frame, each connection extending across the adjacent main frame side section to the wheel frame, and said connections serving to swing the marker arms laterally inwardly and upwardly relative to the main frame whenever said wheel frame is lowered relative to the main frame.

10. An agricultural implement comprising a main frame, a wheel frame swingably connected with said main frame for generally vertical movement relative thereto, a pair of marker arms swingably connected with said main frame and movable between operative and inoperative positions, an operating connection between each marker arm and the adjacent portion of the wheel frame for raising both marker when said wheel frame is lowered relative to the main frame, a latching connection separate from said operating connections and extending from one marker generally transversely of the main frame to the other marker arm, spring means acting to move said latching connection generally transversely of said main frame when either marker arm is raised, and latch means carried by said main frame and engageable with said latching connection for holding one or the other of said marker arms in a raised position when the wheel frame is raised relative to the main frame.
